UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

REINFORCED ANGLE-BAR FOR RAIL-JOINTS.

1,010,474.

Specification of Letters Patent.

Patented Dec. 5, 1911.

Application filed March 18, 1911. Serial No. 615,309.

To all whom it may concern:

Be it known that I, BENJAMIN WOLHAUPTER, a citizen of the United States, residing at New Rochelle, in the county of West 5 chester and State of New York, have invented certain new and useful Improvements in Reinforced Angle-Bars for Rail-Joints, of which the following is a specification.

This invention relates to an improvement 10 in rail joints, and more particularly to the design and construction of angle bars of the reinforced type.

To this end the invention has in view an improved construction of rail joint embodying 15 in its organization a simple and practical design of reinforced angle bar capable of application to the rails with the same facility and readiness as the ordinary forms of splice bars or fish plates, while at the same 20 time having a substantial center reinforcement that secures a maximum strength of bar with a minimum amount of material, and also including a firm and substantial base support for the rail ends of the joint to 25 rest upon, thus combining in a joint bar all of the desirable features of a central girder reinforcement for the bar, and a base support for the rail ends.

A special object of the invention is to provide 30 a rail base support of novel form and arrangement, that is to say, in the form of a girder element presenting its edge to the downward thrust or pressure of the rails and hence resisting all bending strains in a most 35 effective manner whereby the rail joint as an entirety secures to a maximum extent the stiffness obtained from a deep girder section with the additional strength and distribution of load obtained from a rail-base sup- 40 port.

With these and other objects in view, which will more readily appear to those familiar with the art as the nature of the invention is better understood, the same consists 45 in the novel construction, combination and arrangement of parts, hereinafter more fully described, illustrated and claimed.

The essential features of the invention involved in the carrying out of the objects above indicated, are necessarily susceptible of structural change without departing from the scope of the invention, but a preferred embodiment thereof is shown in the accompanying drawings, in which—

55 Figure 1 is a perspective view of a rail

joint constructed in accordance with the present invention. Fig. 2 is a transverse sectional view of the joint at the center thereof. Fig. 3 is a view similar to Fig. 1 of a modified form of the joint. Fig. 4 is a transverse sectional view of the modified form of joint shown in Fig. 3, the section being taken at the center of the joint.

Like references designate corresponding parts in the several figures of the drawings.

As shown in the drawings, a rail joint embodying the present invention comprises, in combination with the rails 1 and 2, the oppositely arranged side angle bars 3 and the usual series of joint bolts 4. Hence, the invention involves or requires no change in the general form and manner of setting up the ordinary types of rail joints employing angle bars or splice bars.

Referring particularly to the design and construction of each angle bar 3, the same essentially consists of the upright splice member 5 formed at its upper edge with the usual head 6 engaging beneath the rail head and at its lower edge provided with the inclined outturned foot piece 7 which overlies and rests upon the inclined top surface of the rail flange, said foot piece including at 80 its outer edge the usual spiking flange 7a. These are the usual elements of the conventional angle bar for rail joints, but in addition thereto the present invention contemplates the feature of providing each angle bar 3 with a depending stiffening girder flange 8 which is sheared off along each end 85 from the body of the bar as indicated at 8a so as to provide for the proper placing of the ties and at the same time dispose the said girder flange centrally between the ends of the bar and hence at the center of the joint.

The depending girder flange 8 is formed integrally with the foot piece 7 and is bent downwardly from such foot piece so as to lie within, and project below the edge of the rail flange, but the present invention is not restricted to the dimensions or shape of the girder flange nor to the angle bar nor to any particular angular position for the girder flange, but is desired to provide additional strength and reinforcement, the said girder flange may be formed along its lower edge with a reinforcing rib 9.

A distinctive feature of the present invention resides in cutting out from the metal body of the girder flange 8 an integral sec-

tion 10 and forcibly pressing said section out of the opening 11 left thereby in the girder flange up to a position where it lies in a substantially vertical plane with its upper edge 5 12 arranged to present the supporting surface that engages beneath and supports the rails at the bottom thereof. It will thus be seen that the rail supporting base sections 10 of the angle bars are in the form of girder elements arranged upright and presenting their edges to the downward thrust or pressure of the rails with the result of most effectively resisting the bending strains incident to the pressure of the load. In this 10 connection it may also be noted that the upright base supporting girder elements 10 lie in the vertical plane of the edge reinforcements 9 at the lower edges of the girder flanges 8, and in order that the full depth of 15 the girder may be preserved, there remains at the bottom of the cut-out opening 11, in each bar, an intact lower chord of which the reinforcement 9 forms a part.

In the embodiment of the invention shown 20 in Figs. 3 and 4 of the drawings, there is suggested the modification of cutting and pressing out from each girder flange two upright base supporting girder elements 10^a, one respectively for each rail end. In this 25 modification it will therefore be seen that the rail base supporting sections or girders are arranged respectively at opposite sides of the joint between the meeting ends of the rails, while in the construction shown in 30 Figs. 1 and 2 the single girder elements bridge the joint between the meeting ends of

the rails, and engage and support both rail ends.

I claim:

1. An angle bar for rail joints provided with an integral stiffening girder and an upright rail base supporting element displaced from the body of the girder and presenting its edge to the bottom of the rails.

2. An angle bar for rail joints provided with a central depending stiffening girder and with a substantially vertically disposed rail base supporting element displaced from the body of the girder.

3. A reinforced angle bar for rail joints provided with a depending girder flange, and with an upright base supporting girder element cut out of and displaced from the flange and having its upper edge arranged to engage beneath the rails, the girder element 55 lying in the vertical plane of the lower edge of the girder flange.

4. A reinforced angle bar for rail joints provided with a centrally located depending girder flange, and with a vertically disposed rail base supporting girder element cut out of and displaced from the girder flange, said girder flange having an integral lower chord at the bottom of the opening from which the girder element is displaced.

In testimony whereof I hereunto affix my signature in the presence of two witnesses.

BENJAMIN WOLHAUPTER.
